US00D849215S

(12) **United States Design Patent** (10) Patent No.: **US D849,215 S**
Huan et al. (45) Date of Patent: **** May 21, 2019**

(54) **HEAT EXCHANGER**

(71) Applicant: **Danfoss Micro Channel Heat Exchanger (Jiaxing) Co., Ltd., Zhejiang (CN)**

(72) Inventors: **Jin Huan**, Zhejiang (CN); **Jin Junfeng**, Zhejiang (CN); **Lu Xiangxun**, Zhejiang (CN)

(73) Assignee: **DANFOSS MICRO CHANNEL HEAT EXCHANGER (JIAXING) CO., LTD.**, Zhejiang (CN)

(**) Term: **15 Years**

(21) Appl. No.: **29/637,666**

(22) Filed: **Feb. 21, 2018**

(57) **CLAIM**

The ornamental design for a heat exchanger, substantially as shown and described.

DESCRIPTION

FIG. 1 is a front, left side and top perspective view of a heat exchanger comprising a new, original and ornamental design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

(Continued)

The broken lines show portions of the heat exchanger that form no part of the claimed design.

1 Claim, 7 Drawing Sheets
